FRANK J. COOK, OF CLEVELAND, OHIO, ASSIGNOR OF SEVENTY-FIVE PER CENT TO
ANNE J. KLEUVER, OF LAKEWOOD, OHIO.

HEATING AND DRYING DEVICE.

Application filed July 6, 1925. Serial No. 41,632.

This invention relates to electric heating devices and is directed more particularly to an electric heating and drying device for printing presses.

5 The primary object of the present invention is to provide a heating and drying device which shall be particularly suited for presses having a reciprocating bed or other movable element over which the 10 printed matter is adapted to pass. The device in this instance is designed as an attachment to such bed or element so as to be movable therewith and including means for creating an air draft over the heating element 15 and against the sheet to be dried.

Another object is to provide a heating and drying device of this general character which shall be simple in construction, inexpensive to manufacture, and which shall 20 be highly efficient and durable in operation.

With these and other objects in view, the invention consists of the various novel features of construction and arrangement or combination, all of which will be fully described hereinafter and pointed out in the appended claims.

In the drawing accompanying and forming part of this application:

Figure 1 is a top plan view of a heater constructed in accordance with my invention;

Figure 2 is an enlarged transverse sectional view taken on the line 2—2 of Figure 1; and

Figure 3 is an enlarged fragmentary top plan view of the heater.

Describing the various parts by reference characters, 1 denotes the heating element supports, which are preferably formed from a fire-resisting material, such as porcelain, 40 lava, or other suitable material. Each of these supports is provided with a plurality of apertures 2 which preferably merge with the top edge 3 thereof so as to permit free expansion and contraction of the supports

45 and heating element 4 without danger of cracking or other damage. The top edges of these supports are slightly arcuate in contour so that a sheet of material resting thereon will be positioned above the heating element and hence avoid any danger of burning or scorching thereof. Each support is formed with a recessed portion adjacent the bottom thereof which defines reversely disposed arcuate edges 5 and feet 6 having

downwardly and inwardly inclined edges 7. 55

In assembling a heating and drying device of this type, I provide a pair of side bars 8 and arrange a suitable number of supports 1 therebetween in accordance with the length of device that is desired. These supports 60 and bars may be fastened together by screws 9 inserted through one side bar and a support and threaded in the opposite side bar as indicated in dotted lines in Figure 3.

In order to create an air draft over the 65 heating element and against the sheet or other object to be dried, and thus greatly expedite the drying thereof, I position a sheet metal deflector plate 10 in contact with the reversely disposed arcuate edges 5 of the 70 supports as clearly shown in Figures 1 and 2. This plate is preferably formed from sheet aluminum to utilize the polished surface thereof as a reflector and thus increase the efficiency of the device. A plurality of 75 bolts 11 extend through offset lugs 13 on the supports and also through the deflector plate, and these bolts are each fitted with a washer 14 and a nut 15 to retain said plate in contact with edges 5. The side edges 80 of the deflector plate are retained in position by the downwardly and inwardly inclined edges 7 of the supports.

The heater is fastened transversely of the bed, or other reciprocating part of the 85 press, by brackets 16 that are clamped to a rod 17 or other suitable support on the press. The ends of the heating element are connected to a terminal block 18 that is fastened between the ends of side bars 8, so that 90 such element may be easily and quickly connected to a source of electric current. In Figure 2 I have shown each support provided with apertures 19 so that a third wire (not shown) may be connected at the mid 95 point of the heating element to provide a variable heat control in the usual and well-known manner.

In operation, the heater being disposed transversely of the press, moves in opposite directions therewith, as shown by the arrows in Figure 2, and thus creates an air draft which enters between a side bar 8 and deflector plate 10, and then passes upwardly over the heating element and against the printed matter passing across the heater. The ink is thus subjected to a heated draft as well as heat by direct radiation from the 100 105

device, and such draft serves to support the printed sheet during its passage thereover. If the press should stop while a sheet is passing over the heater, the rounded upper edges of the supports 1 would prevent the sheet from coming in contact with the heating elements or close enough to prevent serious injury or fire.

While I have described my heater as being particularly suited for presses having a reciprocating bed so as to be movable therewith, it will be obvious that it may be fastened to a stationary part of the press and effect the drying by direct radiation and such natural air draft as would be created by the heated element 4.

What I claim is:

1. A heating and drying device comprising a plurality of supports formed from fire-resistant material, an electric heating element carried by said supports, and a deflector plate arranged beneath said heating element and adapted to direct an air draft over said heating element upon movement of said device.

2. A heating and drying device comprising a plurality of supports formed from fire-resistant material, an electric heating element carried by said supports, and a deflector plate arranged beneath said heating element, said plate having reversely disposed curved portions adapted to create an air draft over said heating element upon movement of said device in opposite directions.

3. A heating and drying device comprising a plurality of supports formed from fire-resistant material, an electric heating element carried by said supports, side bars connecting said supports, and a deflector carried by said supports and spaced from said side bars for directing an air draft over said

heating element upon movement of said device.

4. A heating and drying device comprising a plurality of supports formed from fire-resistant material, said supports having apertures therein adapted to receive an electric heating element and said supports each having an arcuate upper edge, side bars connecting said supports, and a reflector arranged beneath said supports.

5. A heating and drying device comprising a plurality of supports formed from fire-resistant material, said supports each having an arcuate upper edge and apertures intersecting said edge adjacent each end thereof, an electric heating element positioned in said apertures, and means for deflecting an air draft upwardly through said device and about said heating element upon movement of said device.

6. A heating and drying device comprising a plurality of supports formed from fire-resistant material, each of said supports having apertures therein to receive an electric heating element and a recess therein defining reversely disposed arcuate edges, and a deflector plate having reversely disposed curved portions seated against said edges.

7. A heating and drying device comprising a plurality of supports formed from fire-resistant material, each of said supports having an arcuate upper edge and apertures intersecting said edge adjacent each end thereof, a heating element positioned within said apertures, side bars connecting said supports, and a curved deflector plate arranged beneath said heating element and spaced from said side bars.

In testimony whereof I affix my signature.

FRANK J. COOK.
